(57) **CLAIM**

I claim the ornamental design for a sheet pile connector, as shown and described.

DESCRIPTION

FIG. 1 is a perspective view of a sheet pile connector; and, FIG. 2 is a front elevation view thereof.

The front and rear of the design are mirror images of one another, and so only the front elevation view is shown.

The elements shown in broken lines show portions of the article and form no part of the claimed design.
